CLAIM

The ornamental design for a display for automobile interior as shown and described.

DESCRIPTION

1. Display for automobile interior

1.1 : Perspective

1.2 : Bottom perspective view

1.3 : Front

1.4 : Back

1.5 : Left

1.6 : Right

1.7 : Top

1.8 : Bottom

1.9 : Perspective

1.10 : Bottom perspective view

1.11 : Front

1.12 : Back

1.13 : Left

1.14 : Right

1.15 : Top

(Continued)

1.16 : Bottom
1.17 : Perspective
1.18 : Bottom perspective view

1.19 : Front
1.20 : Back

1.21 : Left
1.22 : Right
1.23 : Top

1.24 : Bottom
1.25 : Perspective

1.26 : Bottom perspective view
1.27 : Front
1.28 : Back
1.29 : Left
1.30 : Right
1.31 : Top
1.32 : Bottom

Reproduction 1.1 to 1.8 show the claimed design in the first position; reproduction 1.9 to 1.16 show the claimed design in the second position; reproduction 1.17 to 1.24 show the claimed design in the third position; reproduction 1.25 to 1.32 show the claimed design in the fourth position.

1 Claim, 32 Drawing Sheets
